DESIGN FOR A CONTAINER

William Gerard Martin, Jr., St. George, Staten Island, N. Y.

Application March 16, 1940, Serial No. 90,984

Term of patent 7 years

To all whom it may concern:

Be it known that I, William Gerard Martin, Jr., a citizen of the United States and resident of St. George, Staten Island, county of Richmond, and State of New York, have invented a new, original, and ornamental Design for a Container, of which the following is a specification, reference being had to the accompanying drawing, forming part thereof.

Fig. 1 is a front elevational view of a container showing my new design; and

Fig. 2 is a bottom plan view thereof.

I claim:

The ornamental design for a container, as shown.

WILLIAM GERARD MARTIN, JR.
